SEWING MACHINE GUIDE ATTACHMENT

George Becker, Brooklyn, N. Y.

Application July 13, 1948, Serial No. 38,447

1 Claim. (Cl. 112—153)

1 This invention relates to sewing machine guide attachments.

It is an object of the present invention to provide a guide attachment adapted to be secured to the sewing machine head about the sleeve through which the needle is extended and which has guide members adapted to be extended onto the material being stitched so as to provide guides between which the cloth or material is extended or maintained by the operator while the stitching operation is being performed whereby a straight stitching line will be maintained at all times an equal distance from the edge of the material and wherein a folded over hem will be retained between the guide members while the stitching is being effected.

It is another object of the present invention to provide in a guide attachment for sewing machines angularly adjustable guide elements which when not in use can be lifted and automatically retained in an elevated position and which will be retained in its lowered position against spring action upon a square surface of the element retaining the guide arm.

Other objects of the present invention are to provide a sewing machine guide attachment which is of simple construction, easy to adjust, easy to rearrange for different operations, inexpensive to manufacture, rugged, compact, and efficient in operation.

For other objects and for a better understanding of the invention, reference may be had to the following detailed description taken in connection with the accompanying drawing, in which

Fig. 1 is a perspective view of a sewing machine and of the attachment connected therewith with the guide arms extended into engagement with material being stitched.

Fig. 2 is a sectional view taken on line 2—2 of Fig. 1, but with the guide arms arranged in an opposing relationship as when the attachment is being used to retain a hem which is being stitched.

Fig. 3 is a top plan view of the attachment with the arms arranged as in Fig. 1.

Fig. 4 is a side elevational view of the attachment with one of the guide arms lifted.

Fig. 5 is a fragmentary perspective view of the retaining springs for one of the guide arms.

Referring now to the figures, 10 represents a sewing machine table having a sewing machine head 11 extending upwardly from the same and over the table. Depending from the head or arbor is a sleeve projection 12 through which needle 13 is operated. A thread 14 extends to the 55

needle. Upon this depending projection 12 may be attached my stitching guide attachment 15. This attachment comprises a main body 16 having a split opening 17 for receiving the projection 12. A screw 18 fixes the body to the projection 12.

Extending through the body are parallel threaded openings 21 and 22 for receiving respectively adjustable threaded sleeves 23 and 24 having respectively head portions 25 with flat faces 26 and 27 thereon angularly disposed from one another and against which may bear leaf retaining springs 28, Fig. 5. Adjacent the face 26 is a shoulder 29 adapted to limit the downward turning movement of the screw. Extending through each screw 23 and 24 is a guide arm. In the screw 24 is a guide arm 31 while in the screw 23 is a guide arm 32. The guide arm 32 is larger than the guide arm 31.

The guide arm 31 has a short shank 33 extending through the sleeve 24 and a crooked portion 34 having a rounded foot or engaging formation 35 thereon. In each head 25 is a set screw 36 for securing the shank of the guide arm to the sleeve, Fig. 4.

The guide arm 32 has a long shank 36' which is extended through the sleeve 23, a crooked portion 37 with a foot or engaging formation 38. The leaf springs are fixed to the bottom face of the body 16 by screws 41.

The guide arms 31 and 32 can be arranged as shown in Figs. 1 and 3 or may be arranged as shown in Figs. 2 and 4 and extending from the opposite sides of the body 16. When the guide arms are arranged as shown in Figs. 1 and 3, their crooked portions will lie on the same side of the body and the engaging formations 35 and 38 respectively will lie parallel with one another on the same side of the needle 13. The outer formation 38 will preferably lie at the edge of cloth material as shown in Fig. 1 while the formation 35 will lie just inside of the needle and adjacent the stitching line as indicated at 45, Fig. 1. This formation 35 will hold the cloth in place on the table while the needle 13 operates beside it. The respective heads 25 of the sleeves will lie on the respective opposite sides of the body 16.

With the arms down, shoulder 29 on head 25 will engage the side of the spring 28 and be prevented from further rotation in a down position. If it is desired to raise one of the arms, the same will be lifted upwardly and the spring extended over the face 27 as shown in Fig. 4 whereby to keep the arm elevated.

If the guide arms are arranged as shown in

Figs. 2 and 4, the formations 35 and 38 may receive a hem 41 of the cloth material 44 and the hem may be secured by a stitching 48.

It should now be apparent that there has been provided a simple guide arrangement for sewing machines which can be easily adjusted between use and out-of-use positions without the necessity of having to use a tool or without having to loosen screws. The guide arms 31 and 32 can be easily elevated from their down positions and will be automatically retained in their out-of-use positions by the same springs which hold them in their used positions. When one of the guide arms is not needed, it is simply flipped upwardly. The sleeves 23 and 24 being threaded within their respective openings to prevent the axial displacement of the arms when in use.

While various changes may be made in the detail construction, it shall be understood that such changes shall be within the spirit and scope of the present invention as defined by the appended claim.

I claim:

A sewing machine guide attachment comprising a main body adapted to be clamped to a sewing machine head, said body having a threaded horizontally-extending opening and a bottom

face, a threaded sleeve extending through the threaded opening for pivotal adjustment therein, said threaded sleeve having a head portion with two flat surfaces angled with respect to each other, a guide arm having a shank portion extending through the threaded sleeve, means on the sleeve for locking the shank within the sleeve against rotational and axial displacement with respect thereto, and leaf spring means connected to the bottom face of the main body and extending parallel to the threaded sleeve, said leaf spring means being engageable with the respective flat angled surfaces of the head portion, whereby to retain the guide arm either in its use or out-of-use positions.

GEORGE BECKER.
